(57) **CLAIM**

The ornamental design for a hand held global positioning system, as shown and described.

DESCRIPTION

FIG. 1 is a front perspective view of a hand held global positioning system showing my new design;

FIG. 2 is a top view thereof;

FIG. 3 is a side view thereof;

FIG. 4 is a bottom view thereof;

FIG. 5 is the opposite side view of FIG. 3 thereof;

FIG. 6 is an end view thereof; and,

FIG. 7 is the opposite end view of FIG. 6 thereof.
